UNITED STATES PATENT OFFICE.

B. G. BRIGGS, OF PROVIDENCE, RHODE ISLAND, ASSIGNOR TO HIMSELF
AND T. HILTON, OF SAME PLACE.

DESIGN FOR A PAPER COLLAR.

Specification forming part of Design No. 2,342, dated July 3, 1866.

To all whom it may concern:

Be it known that I, B. G. BRIGGS, of the city and county of Providence, in the State of Rhode Island, have invented a new and ornamental Design for Paper Collars; and I do hereby declare that the following is a full, clear, and exact description thereof, which will enable others skilled in the art to make and use the same, reference being had to the accompanying drawing, forming part of this specification.

The drawing represents an elevation of this invention.

The invention relates to a design composed of a series of ridges of gradually-decreasing width and at gradually-decreasing distances apart in such a manner that a paper collar is produced of a novel and elegant appearance and fit, particularly for ladies.

A represents a paper collar, which is provided with a series of ridges, *a*, of gradually-decreasing width and arranged in such relation to each other that the distance between them decreases in a similar ratio to the decrease in the width of the ridges. Each ridge is provided with an imitation seam, giving to the collar an elegant appearance.

What I claim as new, and desire to secure by Letters Patent, is—

The design for a paper collar, as shown and described.

The above specification of my invention signed by me this 23d day of May, 1866.

B. G. BRIGGS.
